UNITED STATES PATENT OFFICE.

JOHN MILTON VAN ALST, OF JERSEY CITY, NEW JERSEY, ASSIGNOR TO EBERHARD FABER PENCIL COMPANY, OF BROOKLYN, NEW YORK, A CORPORATION OF NEW YORK.

DESIGN FOR A PENCIL-CONTAINER.

47,350.

Specification for Design.

Patented May 11, 1915.

Application filed March 5, 1915. Serial No. 12,429. Term of patent 7 years.

To all whom it may concern:

Be it known that I, JOHN MILTON VAN ALST, a citizen of the United States, residing at Jersey City, in the county of Hudson and State of New Jersey, have invented a new, original, and ornamental Design for Pencil-Containers, of which the following is a specification, reference being had to the accompanying drawing, forming part thereof.

The figure is a perspective view of a pencil container showing my new design.

I claim—

The ornamental design for a pencil container as shown.

JOHN MILTON VAN ALST.
